Primary Examiner — Eliza Z Harvey

Assistant Examiner — Kayla Marie Bennett

(57) **CLAIM**

The ornamental design for a furniture riser, as shown and described.

DESCRIPTION

FIG. 1 is a top perspective view of a furniture riser design showing my new design.

FIG. 2 is a bottom perspective view of a furniture riser.

FIG. 3 is a front view of a furniture riser.

FIG. 4 is a rear view of a furniture riser.

FIG. 5 is a left side view of a furniture riser.

FIG. 6 is a right side view of a furniture riser.

FIG. 7 is a top view of a furniture riser.

FIG. 8 is a bottom view of a furniture riser; and,

FIG. 9 is an exploded view of a furniture riser.

Any shading and cross-hatching are not features of the design but are utilized to illustrate the surface contours of the furniture riser design in the drawings.

The broken lines in the drawings depict portions of the furniture riser that form no part of the claimed design.

1 Claim, 9 Drawing Sheets
